UNITED STATES PATENT OFFICE.

FRANK B. BIGELOW, OF DETROIT, MICHIGAN, ASSIGNOR TO MURPHY IRON WORKS, OF DETROIT, MICHIGAN, A CORPORATION OF MICHIGAN.

ARCH CONSTRUCTION FOR FURNACES.

Application filed February 20, 1922. Serial No. 537,719.

To all whom it may concern:

Be it known that I, FRANK B. BIGELOW, a citizen of the United States, residing at Detroit, in the county of Wayne and State of Michigan, have invented certain new and useful Improvements in Arch Constructions for Furnaces, of which the following is a specification.

My present invention concerns the means 10 for supporting the brick arches of furnaces, especially those of the flat type, and similar structures, its chief object or prime purpose being the provision of a novel and improved arch or arch-brick carrying or sustaining means the employment of which 15 will permit a more economical use of the bricks constituting the arch and a better relation of the bricks to one another, particularly the superposed bricks at the sides 20 and back of the furnace.

One aim of the invention is to supply means for supporting the bricks in such a manner that they may be individually replaced when burned out or destroyed and in 25 such a way that the new brick will not be unduly subjected to the heat of the furnace and hence not unnecessarily consumed or deteriorated by such heat.

To this end, the several bricks are supported individually or singly from above, and, as the bricks become gradually burned away or consumed by the heat, they become somewhat thinner and ultimately some of them require replacement.

Under these circumstances, it is desirable 35 that the lower surface of the new brick, used as a substitute for an old one, should register substantially with the corresponding faces of the remaining partly-wasted bricks, 40 and, accordingly, the brick hangers are made adjustable as to length, whereby numerous bricks of different thicknesses may be supported in such a way that their under faces will be practically flush with no brick 45 or bricks unduly or excessively exposed to the consuming or destroying heat.

Stated somewhat differently, after an arch has been in service for a length of time and subject to high furnace temperatures, 50 it decreases in thickness, and in replacing a new brick in an old arch of the known form, the new brick will extend below the under surface of the arch and be exposed to the furnace temperature on five sides, and 55 consequently it is subject to rapid de-

terioration, whereas, in the improved arch of this application, when inserting a new brick, the supporting means therefor can be shortened so as to place the under surface or face of the new brick flush with the 60 balance of the arch, thus securing full life of the new brick and adding materially to the life of the arch.

At the sides of the arch, the marginal 65 bricks are positioned directly above other lower rows of bricks supported on the corresponding arch-plates, and it is desirable that such superposed rows of bricks should be in contact to practically close or seal the joint between them, but at the same time it 70 is essential that there should be no material pressure exerted between such upper and lower rows of bricks because the former constituting a direct part of the flat arch should be capable of substantially unrestrained sidewise or lateral movement due 75 to the varying degrees of heat to which they are subjected.

By means of such adjustable brick hangers or supports just the right relation between such bricks may be easily attained and maintained.

A similar situation is present at the back of the arch and it is cared for in like manner.

In order to enable those skilled in this art to fully understand the structural and functional advantages of a furnace embodying this invention, in the accompanying drawings forming a part of this specification, I have illustrated a desirable and preferred embodiment of the invention and in the several views thereof, like reference characters have been used to designate the same parts.

In these drawings:—

Figure 1 is a fragmentary sectional view taken from the rear of the furnace looking forwardly into the latter, some of the elements of the structure being omitted to more clearly depict the details of construction;

Figure 2 is a fragmentary, longitudinal, vertical section through the back part of the arch showing the supporting means for the bricks;

Figure 3 is vertical, fragmentary cross-section through a part of the arch near one side of the latter; and

Figure 4 is an enlarged vertical section on line 4—4 of Figure 2.

110

In the particular embodiment shown, although as will be obvious to those skilled in this art, the invention may be satisfactorily employed in furnaces of radically different 5 styles, the furnace is of the usual "Murphy" type comprising a V-shaped grate 11, clinker grinder 12, opposed coking-plates 13, 13, associated sidewise-reciprocating stoker-boxes 14, 14, superposed fuel-magazines 15, 15, air-flues 16, 16, longitudinal arch-plates 17, 17, and rows of arch-plate bricks 18, 18, supported on the arch-plates and held or locked in position by appropriate latches 19, the lifting or elevation of which releases the 10 bricks permitting their ready replacement.

The flat suspended arch proper 20 is composed of a plurality of bricks 21 arranged in horizontal, longitudinal and transverse rows, as is clearly depicted in Figure 1, and, 20 when the arch is new, all of these bricks or refractory blocks will be of practically the same thickness and will unitedly present a substantially smooth lower face.

Each such arch-brick has an undercut or 25 inverted T-shaped groove across its top face for the purpose of accommodating or receiving a suitably-shaped transversely apertured shoe 22 having an enlarged lower part occupying the undercut section of the brick 30 cavity.

Each brick shoe of this kind, except those at the side and rear margins of the flat arch, is supported from a pipe 23 above by means of a chain 24 with hook ends 25 and 35 26, the former taking into the eye or hole of the shoe and the latter engaging the appropriate link of the chain to support the brick at the desired or required height, such elevation of the brick obviously being subject to adjustment by catching the hook in any desired link of the chain.

The construction comprises one such upper, apertured or unperforated pipe, as the case may be, for each longitudinal row 45 of bricks, these several pipes being sufficiently high above the bricks to permit the replacement of any one of the latter without disturbance of the others, the pipes being supported by front and rear cross I beams 50 27 of which only the latter is shown in the drawings.

At the front of the furnace such pipes are open to the outer air, but this detail has not been illustrated because it forms no part of 55 the present invention, and as is fully indicated in Figure 2, each such pipe extends rearwardly through a hole in the web of the corresponding I beam projecting back thereof some distance.

60 In the operation of the furnace, outer air, by the draft of the furnace, is drawn in through these several pipes and delivered through their holes or apertures near their rear ends in small jets into the space above 65 the arch, thus keeping the pipes cool and

supplying a portion of the air for carrying on the combustion.

Spaced longitudinal T-bars 28 are mounted on the top of the transverse I-beams and between and supported on these are removable cover tiles 29 which give ready access to the hangers for the bricks of which the arch is composed.

The side marginal or border bricks 31 of the flat arch located partly above the arch-plate bricks 18 are hung from above on the outermost pipes 23 by means of hangers which give great refinement of regulation as to length.

Each such brick has one of the usual shoes 22, but this is suspended from the pipe by a reversely-threaded turn-buckle hanger 32 which gives opportunity for nicety of adjustment as to length thus accurately governing or gauging the position of the brick 85 which it supports.

The flat under surface of each brick 31 must bear on the top plane face of the corresponding lower arch-plate brick with sufficient pressure to assure a comparatively or 90 relatively tight joint between them, but this pressure must not be sufficient or great enough to materially hamper or retard the bodily movement of the upper brick over the lower one as is caused by the expansion and 95 contraction of the arch under the wide range of temperatures to which it is subjected.

At the rear of the furnace, the projecting part of each pipe 23 supports an apertured 100 sealing-brick 33 mounted directly on the end of the pipe by the reception of the latter in its cavity, the brick or block being held in place on the pipe by a pipe-plug 34 maintained in position by a catch 35 inside of 105 and having a downturned end engaging a hole in the pipe.

The part of the brick recess accommodating the plug but not occupied by the latter is filled by a fire-clay plug 36, all as is 110 fully illustrated in Figure 2 and as will be readily understood.

The end-bricks 37 of the arch are of the cross-sectional shape indicated in Figure 2, and they are individually or separately supported on the several pipes by turn-buckle or other suitable hangers 38 in much the same manner that the bricks 31 are held in place.

The accurate and delicate screw-thread adjustment permitted by such hangers allows the co-acting flat faces of the bricks 37 and 33 to be brought into and kept in proper contact under all conditions of service, thus rendering certain and guaranteeing the correct tightness or seal of the joint without interference with the necessary relative movements of these parts by reason of expansion and contraction of the elements of the structure subjected to the heat of the furnace.

130

In Figure 1 of the drawing all of the bricks of the main body of the arch are of the same thickness and their hangers are adjusted for uniform length. This condition could well represent the construction when it is first installed.

In Figures 2 and 3 the bricks or refractory blocks are of different thicknesses and their hangers or supporters have been adjusted accordingly to cause them to present a practically smooth under surface exposed to the direct heat of the furnace.

An arch of this general character usually requires repairing rather than the renewal of the entire arch, and if a local deterioration can be repaired easily and inexpensively, as is permitted by this improved construction, the life of the arch as a whole is lengthened many times.

20 In this new structure, the space at the rear of the arch is closed by special bricks or blocks, so attached or supported that they cannot be forced off of the supporting members by the expansion of the arch and 25 at the same time the construction keeps the joints tight thus avoiding an inefficient operation of the furnace or an injurious flow or passage of the heated gaseous products of combustion.

30 It should be noted in passing that the arch-plate bricks are independently supported or held in place and can be quickly and easily removed and replaced without interfering with any other portion of the arch.

35 Thus every brick in the arch is independently supported and can be taken out and replaced without disturbing the balance of the arch.

The present improved construction, as will 40 be understood without difficulty, provides for the elimination of expansion strains, and the cracking and spalling of bricks due to the expansion and pressure of adjoining bricks.

45 The invention is not limited and restricted to the precise and exact details of structure shown and described since these may be modified within radical limits without departure from the heart and essence of the 50 invention and without the sacrifice of any of its substantial benefits and advantages.

I claim:

1. In a furnace arch structure, the combination of an arch-plate, an arch-plate brick mounted thereon, a brick arch having a border brick at least in part over said arch-plate brick, and means supporting said border brick from above and capable of permitting variation in the contactual relation of such arch-plate and border bricks.

2. In a furnace arch structure, the combination of an arch-plate, a row of arch-plate bricks mounted thereon, a brick arch having a border row of bricks each of 65 which at least in part is over the row of

arch-plate bricks, and adjustable means supporting said border bricks independently from above to permit regulation of the contactual relation of the border bricks with the arch-plate bricks.

70

3. In a furnace arch structure, the combination of an arch-plate, a row of arch-plate bricks mounted thereon, a brick arch composed of a plurality of bricks, means adjustable as to length supporting said bricks 75 independently from above, whereby the under surface of the arch may be maintained substantially smooth even though the bricks are of different thicknesses, said arch having a border row of bricks each of which at least in part is over the row of arch-plate bricks, and adjustable means supporting said border bricks independently from above to permit regulation of the contactual relation of the border bricks with the arch-plate 80 bricks.

4. In a furnace arch structure, the combination of a brick arch, means to support the arch, a row of sealing bricks at the rear of the arch, means to support said sealing 90 bricks, a row of end bricks for the arch below said sealing bricks, and means adjustable as to length supporting only said end bricks individually from above, whereby the contactual relation of said end and sealing bricks may be controlled to maintain the joints between them substantially tight but without material interference with the expansion and contraction of the arch.

5. In a furnace arch structure, the combination of a plurality of spaced supports disposed lengthwise the furnace, opposed arch-plates, rows of arch-plate bricks mounted on said arch-plates, an arch composed of a plurality of bricks including rows of border 100 bricks at least in part located over said arch-plate bricks, means adjustable as to length supporting the bricks of said arch individually from above from said spaced supports, whereby a practically smooth under surface of the arch may be maintained even though the bricks thereof are of different thicknesses, and whereby the joints between the border and arch-plate 105 bricks may be maintained practically tight without substantial interference with the expansion and contraction of the arch, a row of sealing bricks at the rear of the furnace mounted on said spaced supports, a row of end bricks for the arch below said sealing bricks, and means adjustable as to length supporting said end bricks individually from above whereby the contactual relation of said end and sealing bricks may be controlled to maintain the joints between 110 them substantially tight but without material interference with the expansion and contraction of the arch.

6. In a furnace arch structure, the combination of an arch-plate, a row of arch-plate bricks mounted thereon, a brick arch having a border row of bricks each of which at least in part is over the row of 115

120

125
